UNITED STATES PATENT OFFICE.

MARION MALLORY, OF TOLEDO, OHIO, ASSIGNOR TO MALLORY ELECTRIC CORPORATION, OF TOLEDO, OHIO, A CORPORATION OF OHIO.

SELF-INDUCTION PRODUCER.

Application filed December 18, 1924. Serial No. 756,656.

My invention has for its object to provide a simple means whereby the ordinary vibrating spark coils commonly used for engine ignition may be readily converted into non-vibrating coils that may be efficiently used for the same purpose.

In induction coils of the vibrating type the primaries of the coils have a low resistance and moreover they do not have sufficient self-induction to produce a counter electro-motive force in the primary coil that will prevent substantially free flow of a direct constant current through the coil. When, therefore, automobile batteries are connected to such coils through the ordinary cam controlled circuit closers, the coils become over heated and the batteries are soon exhausted. If sufficient resistances are inserted in the coil and battery circuits to prevent early exhaustion of the batteries, the current produced is so weak that ignition becomes deficient. In the ordinary magneto operated ignition coil, such as that found in the ordinary Ford automobile, four induction coils are placed, side by side, in position, each having a relatively small core, and a low resistance primary. Also a reed circuit breaker operates to rapidly open and close the circuit of each primary coil. The magneto is connected to the engine shaft so that maximum parts of the potential wave will be in synchronism with the ignition timer of the engine. The timer is located in the circuit that connects the primaries of the induction coils in the order that the spark plugs, connected to the secondary coils, are to be fired. When a battery, controlled by a circuit closer operated synchronously with the pistons of the engine, is connected to the primaries in succession, the reed vibrator interferes with the circuit closer's action and hence the vibrator must be short circuited or eliminated. Since the spark is produced on the break of the circuit closer, it maintains a relatively long total period of current flow through the low resistance and low self induction primary coils, which soon destroys the battery.

When the coils of the vibrating type are connected to a battery, the points burn and pit and are soon destroyed, which requires continual adjustment and cleaning.

By my invention I decrease the reluctance of the field of one or more of the induction coils which increases the self induction of

the coil when the vibrating reed is moved or short circuited and is used with a cam operated circuit closer. The decrease of the reluctance produces a counter electro-motive force that cuts down the battery current and yet produces the maximum number of lines of force producable by the current of the battery within the time that the circuit closer is closed, and so that when the circuit is broken a maximum induced current is produced in the secondary coil. Preferably I do this by using one of the induction coils for the electric transformation and the cores of the coil and of the adjoining coil for increasing the self induction. Thus I utilize what is already supplied in connection with a Ford automobile or other automobiles having a plurality of vibrating coils. This is preferably done by placing a magnetic body of sufficient size in contact with the upper or lower ends of the two cores. The same may also be accomplished by placing a body formed of magnetic material in contact with one end of the core of one of the coils, the body extending to a point in the vicinity of the other end of the core of the coil. Thus I am able to readily change a vibrating spark ignition system to a single spark system.

The arrangement and structure of the parts, however, may be greatly varied and still be within the purview or the scope of the claims for my invention hereinafter appended. To illustrate a practical application of the invention I have selected two or three forms of structures containing the invention, and illustrative ignition systems involving the use of my invention and shall describe them hereinafter. The structures selected and the systems referred to are shown in the accompanying drawings.

Figure 1 of the drawings illustrates a top view of an induction coil, or unit of the type commonly used in the Ford automobile. This unit is commonly referred to as a vibrating spark. Fig. 2 is a side view of a top portion of the coil illustrated in Fig. 1. Fig. 3 illustrates a pair of coils, like that shown in Figs. 1 and 2, modified so as to embody my invention. Fig. 4 illustrates a side view of the coils shown in Fig. 3. Fig. 5 is a diagrammatic illustration showing the extension of the field through the magnetic material of the coils whereby the self induction of one of the coils or of both of the

2
coils, if both are connected in the ignition circuits, is greatly increased. Fig. 6 is a diagram of a system that may be used where a plurality of induction coils, furnished with the ordinary automobile, are utilized in connection with a battery ignition system and which involves the use of my invention.

It has been found by owners of cars that when they have changed their ignition systems from the vibrating spark system to a single spark system the battery soon becomes exhausted. In order to maintain the battery in its normal condition and yet utilize the induction coils furnished with the car to reduce the cost of installation, various expedients have been used or followed. These, however, have resulted in so weakening the current directed through this, the ignition part of the automobile electric system, that the ignition is even less efficient than the original vibrating spark system, and frequently causes failure in the ignition of the engine cylinders. Also a special coil of the non-vibrating type is used, but this adds greatly to the cost of the installation of the system. By my invention I have provided a means whereby the coil furnished with the machine may be used and yet produce the same efficiency that may be produced by special single spark coil. In the use of my invention the current within each primary coil of one or more of the induction coils will be automatically retarded to a desired degree and until the desired number of lines of force are created, such as to produce a flaming arc or spark of the required temperature at the terminals of the spark plugs in the engine cylinders, whereby ignition will be assured, notwithstanding the change from the vibrating spark ignition system to the single spark ignition system by the use of coils that constitute "standard" parts of the automobile of that particular type. The invention is particularly applicable to the ignition systems of Ford automobiles wherein induction coils of the type shown in Figs. 1 and 2 of the drawings are commonly used in connection with the well known Ford magneto.

50 The induction coils are located in receptacles 1 and are each provided with a vibrating reed 2, that is anchored to a conductor member 3. A pair of "points" 4 are secured one to the reed 2 and the other to an adjustable bridge 5. The bridge 5 is supported in position by uprights 6, one of which may form a binding post to establish electric connection with one of the points 4, and its position relative to the reed 2, is adjusted by means of the thumb nut 7 located in the threaded post 8. Thus the points 4 may be adjusted one relative to the other. The induction coil is connected in the Ford ignition system in the manner well known in the art.

Also, as well known, the primary coil is of low resistance and the induction coil, as a whole, has a very low self induction and consequently when the induction coil is used for producing ignition sparks at the terminals of the spark plugs in a single spark system, the battery is rapidly discharged as its maximum output is utilized during the period in which the circuit closer is closed. Furthermore, it has been found difficult and quite impossible to accurately operate the well known cam controlled circuit closer to cause periodic closing of the circuit to reduce the total period, in which the full effectiveness of the battery is utilized in the ignition system. To shorten the period of closing of the circuit of the primary coil renders uncertain the operation of the system and makes practically impossible accurate adjustments to attain a satisfactory ignition of the engine. In converting the vibrating ignition system to a single spark ignition system, the reed 2 is removed and the wire 10 is connected at one end to the conductor member 3, and the other end to the binding post 4. Where two of the induction coils are to be used, the coils of one to be connected in the electric circuits and the core of the other to decrease the reluctance and increase the self induction, the alterations are also made in connection with a second coil. If desired substantially the same arrangement existing in connection to the vibrating system may be utilized in connection with the single spark system, in that the four coils may be used successively for producing the ignitions of the cylinders at the proper times in the cycle of operations of the pistons. In that case the four induction coils are modified as described. Whether two or four coils are used to produce the ignition, and to increase the self induction, they are joined together in pairs by a bar 11 of magnetic material, that extends across the upper ends of the cores 12 which protrude from the receptacle. They are preferably secured in position so as to make contact with the said ends of the cores. The bar 11 is also preferably formed of laminated magnetic material. The bar 11 decreases the reluctance and increases the quantity of the magnetic material through which the lines of force produced by the coil connected with the battery may extend and consequently greatly increases the number of lines of force produced by the coil. When, therefore, the battery is connected to the primary of the induction coil the large self induction that is produced greatly reduces the quantity of the current that flows from the battery by reason of the production of the large counter electro-motive force, which requires time to overcome.

The electrical connections may be varied as may be desired to produce the arcs at the

terminals of the spark plugs. In the form of system shown in Fig. 6 wherein the four induction coils are utilized to produce the ignition of the engine, the battery 13 is connected to the primaries 14 and the primaries are in turn connected to the contacts 15, of the distributor, while the rotatable arm 16 is connected to the circuit closer 17 having the cam 18. The arm 16 and the cam 18 are connected to the "cam shaft" of the engine which is connected in the usual ratio with the driving shaft of the engine. A condenser 19 is connected across the circuit closer to reduce the arcing at the points or contacts of the circuit closer. The distributor and circuit closer, that is the timer may be constructed in the manner well known in the art, that is, any of the well known timers may be used. Thus the circuit of the battery is periodically closed through the primaries in succession, and, while the circuit is closed through each primary, the circuit closer 17 is opened to break the circuit through the primary and de-energize the primary coil. This produces a high tension current in the secondary of the induction coil. The secondary coils 20 of the induction coils are connected to the spark plugs 21 and consequently the high tension current produced in the secondary coil by the de-energization of a primary coil produces an arc at the terminals of the spark plugs. In the form of system shown in Fig. 6 the magnetic bars 11 being connected across the cores of pairs of induction coils increases the self induction of either of the coils when it is connected to the battery through the timer, and so that the core of the other coil will constitute a part of the magnetic circuit of the coil that is thus connected.

I claim:—

1. In combination with a pair of induction coils located side by side, each having a core and primary and secondary coils, a re-

movable bar of magnetic material magnetically connecting the cores of the induction coils. 45

2. In combination with a pair of induction coils located side by side, each having a core and primary and secondary coils, a bar 50 of magnetic material, a threaded means for removably securing the bar in position to magnetically connect the cores of the induction coils.

3. In combination with a pair of induction coils located side by side, each having a core and primary and secondary coils, a bar of magnetic material, the bar having ears, a threaded means extending through the ears for removably securing the bar in 60 position to magnetically connect the cores of the induction coils. 55

4. In combination with a pair of Ford induction coils, each having a core and primary and secondary coils, a container 65 for each coil, threaded posts located on the ends of the container, a bar of magnetic material magnetically connecting the cores of the induction coils and secured in position by the threaded posts. 70

5. In combination with a pair of Ford induction coils, each having a core and primary and secondary coils, a container for each coil, threaded posts located on the ends of the container, a bar of magnetic material magnetically connecting the cores of the induction coils, the bar having an ear 75 for receiving the threaded post, the post having a nut for securing the bar in position. 80

6. In combination with a plurality of closely positioned coils, means for decreasing the reluctance of the coils, comprising a magnetic keeper across the ends of the cores of said coils. 85

In testimony whereof, I have hereunto signed my name to this specification.

MARION MALLORY.
